Patented Apr. 5, 1966

204,265

DRAPEY SLIDE FOR A CURTAIN ROD

Samuel Galietti, 1360 NE. 204th Terrace,
North Miami Beach, Fla.

Filed Nov. 20, 1964, Ser. No. 82,729

Term of patent 14 years

(Cl. D21—1)

FIG. 1

FIG. 2

FIG. 3

FIG. 4

FIG. 5

FIGURE 1 is a side elevational view of a drapery slide for a curtain rod showing my new design,

FIGURE 2 is a side elevation from the opposite side thereof,

FIGURE 3 is an edge view thereof,

FIGURE 4 is a top plan view thereof, and

FIGURE 5 is a bottom plan view thereof.

I claim:

The ornamental design for a drapery slide for a curtain rod as shown.
